WIRE LINE BAILER FOR PICKING UP JUNK
IN OIL WELL BORES

Wayne N. Sutliff, Bakersfield, Calif.

Application June 1, 1951, Serial No. 229,390

4 Claims. (Cl. 166—19)

1

The present invention relates to devices for removing debris from well bores.

An object of the present invention is to provide an improved catcher apparatus for entrapping debris in a well bore and removing it to the top of the hole, without danger of any portion of the debris dropping out of the catcher.

Another object of the invention is to provide an improved catcher for entrapping debris in a well bore, which is capable of being lowered in the well bore on a wire line, and in which the catcher can be forcibly moved downwardly in the well bore, if necessary to insure the passage of the debris into the catcher.

A further object of the invention is to provide an improved check valve or one-way holding device that will allow debris to enter the catcher, but which will automatically close to prevent dropping of the debris from the catcher.

Yet another object of the invention is to provide an improved check valve or one-way device that will prevent entrapped debris from dropping from the catcher despite the presence of some debris in the device itself tending to prevent its full closing.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a longitudinal section through a debris catcher embodying the invention, with the upper portion shown partly in elevation, the parts of the device occupying their relative positions while being lowered through a well bore;

Fig. 2 is a view similar to Fig. 1, illustrating the device while being elevated in the well bore;

Fig. 3 is a cross-section taken along the line 3—3 on Fig. 1;

Fig. 4 is an isometric view of the one-way valve or holding portion of the device;

Fig. 5 is a view similar to Fig. 4, with a portion of the valve device in longitudinal section;

Fig. 6 is a cross-section taken along the line 6—6 on Fig. 2;

Fig. 7 is a view similar to Fig. 6, with the valve disclosed in open position;

2

Fig. 8 is a longitudinal section taken along the line 8—8 on Fig. 6;

Fig. 9 is a cross-section taken along the line 9—9 on Fig. 8.

The debris catcher disclosed in the drawings can be lowered in the well bore on any suitable running-in string, such as a wire line (not shown). The catcher includes a generally cylindrical chamber or barrel 10 having an upper head 11 threaded thereinto, and adapted to be closed at its lower portion by a one-way check valve or holding device 12. This check valve is made of a pliant, elastic material, such as natural or synthetic rubber, having its lower portion molded onto a retainer ring or protector 13, which is clamped against the lower end of the barrel 10 by a clamp ring 14 threaded into an adapter sleeve 15 welded, or otherwise suitably secured, to the barrel.

Disposed around the exterior of the lower portion of the barrel 10, and also around the adapter sleeve 15 and clamp ring 14, is a shoe 16 having a downwardly flaring lower portion 17. The cylindrical sleeve portion 18 of this shoe is slideable along the adapter 14 and clamp ring 13 and terminates in an inwardly directed flange 19 that is slideable along the outer surface of the barrel or chamber 10. The lower portion of the barrel or chamber is provided with a plurality of side ports or holes 20, which are open when the shoe 16 occupies a lower position with respect to the barrel 10, and which are closed by the shoe flange 19 when the shoe occupies an upper position with respect to the barrel. This last-mentioned position is determined by engagement of the upper end of the shoe with a stop ring 21 welded, or otherwise suitably secured, to the barrel 10. The lower position of the shoe is determined by engagement of the flange 19 with the upper end of the adapter sleeve 15, in which position the side holes are open.

The apparatus also includes a jarring member 22 of suitable weight secured to the wire line, or other running-in string (not shown), which member is attached to a sinker rod 23 extending slidably through the upper barrel head 11. A valve head 24 is integral with, or secured to, the lower end of the sinker rod 23 and is disposed within the barrel 10. This valve head has a plurality of longitudinally extending passages 24a through which fluid moving upwardly in the barrel can pass, for discharge through bleeder or exhaust ports 25 formed in the barrel 55 immediately below its head 11. A perforated

strainer 26 is preferably disposed at the lower end of the valve head 24, being secured thereto by a screw 27.

When the sinker rod 23 and attached head 24 are lowered with respect to the barrel, the exhaust ports are open 25, and any fluid entering the barrel can pass upwardly through the strainer 26 and head passages 24a for outward flow through the exhaust ports 25. When the sinker rod 23 and its attached head 24 are elevated with respect to the barrel 10, the valve head 24 moves over the exhaust ports 25, to close them and also to prevent passage of the well fluid through those ports into the chamber 10.

The shoe 16 may be provided with one or more by-pass ports 28, to allow liquid and possibly comparatively small particles to by-pass the shoe during movement of the apparatus through the well bore. Such particles are small enough as not to be classified as junk or debris that might interfere with the running of other tools in the well bore.

Upwardly inclined baffles 29 may also be provided in the chamber 10, being secured to the barrel and serving to aid in supporting the debris D that might enter the barrel, relieving the one-way valve member 12 of the load of such debris. If desired, however, the baffles may be omitted, since the one-way valve member is sufficiently strong to support a full load of debris in the barrel.

The apparatus is run in the well bore, as on the lower end of a wire line, and during such lowering through the well bore, the parts occupy the position illustrated in Fig. 1. When in this position, the sinker rod 23 and attached head 24 are shifted downwardly within the barrel 10, to uncover the bleeder or exhaust ports 25 and the shoe 16 is elevated with respect to the barrel to cover or close the drain holes 20. The fluid in the well bore may by-pass around the shoe 16, some of the fluid entering the flaring portion 17 of the shoe passing outwardly through the by-pass ports 28 without entering the barrel or chamber 10. Any large particles of debris and junk encountered in the well bore, however, will pass upwardly against the underside of the check valve 12, opening the latter, in the manner described below, and entering the chamber 10. Liquid or other fluid comingled with the debris can pass upwardly through the strainer 26 and head passages 24a, for discharge through the exhaust ports 25.

When it is desired to remove the apparatus from the well bore, the running-in string is elevated, which shifts the sinker bar 23 upwardly and the valve head 24 across the bleeder ports 25, closing the latter. Such upward movement will also move the shoe 16 relatively to its lower position, disclosed in Fig. 2, in which the drain holes 20 are open. In view of the one-way characteristics of the valve, it will close upon upward movement of the apparatus; so that any debris D that might be entrapped within the barrel 10 is prevented from dropping therefrom. During elevation of the apparatus in the well bore, the well fluid is incapable of entering the barrel through the bleeder ports 25, since they are closed. However, any liquid that might be contained within the barrel can drain outwardly through the open bleeder holes 20 at its lower portion. In addition, fluid in the well bore on the exterior of the apparatus can by-pass the apparatus by passing through the shoe ports 28, as

well as around the lower flaring end 17 of the shoe.

When the top of the well bore is reached, the apparatus can be dismantled and the contents of the barrel dumped.

In the event resistance to downward movement is encountered when the equipment is being lowered in the well casing, it is possible to impart an impact blow or jarring action on the barrel 10, to force its shoe 16 over the debris D, and cause the latter to pass through the check valve 12 and enter the barrel. The resistance to downward movement may result in stopping of the bailer, whereupon, the wire line can be reciprocated, to repeatedly drop the jarring member 22 upon the upper barrel head 11, which will force the shoe 16 over or through the debris. If upward jarring is necessary, the valve head 24 attached to the sinker rod 23 can be elevated to strike a blow against the lower end of the upper barrel head 11.

The one-way valve or holding element 12 permits fluid, junk or other debris to enter the bailer, but will preclude its dropping therefrom. In addition, if any debris tends to become stuck in the valve, the latter will close around such debris and still maintain a substantially closed position; so as to prevent the bailer contents from dropping out during elevation of the apparatus in the well bore.

As disclosed in the drawings, the one-way valve or holding device includes a hollow, generally dome-like body 40 that may be of generally ogive shape. The body is disposed around the upwardly projecting rim 41 of the retainer or protector ring 13, with the inner portion 42 of the body disposed along the inner face of the ring. The rubber body 40 is molded, or otherwise suitably secured, to the protector member 13 and its skirt 41 to provide a secure joint between the two.

Integral with the central, dome-like body portion 40 of the valve element are a plurality of laterally extending ribs 43 that extend outwardly from the axis of the valve member to a point adjacent the outermost portion of the body. The upper ends 44 of the ribs may be substantially at right angles to the axis of the body, and the ribs are each of substantial thickness; so as to reinforce the body and make the entire valve structure capable of supporting a large load of debris D within the chamber or barrel 10.

As shown in the drawings, four ribs 43 are disposed in circumferentially spaced relation around the elastic body 40, with their upper portions integral with one another; so as to, in effect, form a cross. Each rib is slotted or severed generally radially of the axis of the valve device, the slot 45 extending downwardly through the body 40 to its exterior. Here again, the slots in all of the ribs form a slotted cross.

The rib material inherently tends to contract; so that the valve device occupies the normal position, such as disclosed in Fig. 4, in which the slots 45 are all closed, preventing any material above the valve from dropping thereinto. As a matter of fact, the weight of the material acting on the ribs tends to maintain the slots closed. However, upon debris entering the underside of the valve body, such debris will engage the body 40 and stretch it outwardly, the rib material 43 on opposite sides of the slot 45 stretching laterally outward, such as disclosed in Fig. 7, to form a relatively wide opening 45a through which the debris D can pass into the barrel 10 above the

valve. If no debris is inside of the body 40, then the rubber or other elastic material from which the valve member is made will contract and revert to its initial shape, disclosed in Figs. 4 and 6, in which the slots 45 are closed.

It is, accordingly, apparent that during downward passage of the apparatus through the well bore, any debris or junk encountered therein will stretch the valve element 12 laterally, to effect its opening, which will allow the debris to enter the catcher chamber 10. When no debris is pressing upwardly on the valve, the member will reassume its closed shape. If, however, some debris happens to be caught in one or more of the slots 45 of the valve body 40 and ribs 43, as during elevation of the apparatus in the well bore, the ribs will close and substantially seal around the particles of debris in the slot 45, and the remainder of the slot portion and the other slots will still contract to their normal closed position. Accordingly, it is evident that despite the fact that some piece of junk or debris might be caught in the valve member, it is not prevented from closing substantially completely, and, as a result, the valve is not held open; preventing all or part of the contents of the bailed to drop therefrom during elevation of the apparatus in the well bore.

Having thus described my invention, what I claim and desire to secure by Letters Patent is:

1. A bailed adapted to be lowered in a well bore, including a barrel, a check valve at the lower end of said barrel capable of allowing upward passage of substances through said valve and into said barrel, an upper member telescopically arranged with respect to said barrel, said barrel having a bleeder passage therein, means on said upper member for closing said passage when said member occupies an upper position with respect to said barrel, said barrel having a drain hole in its lower portion above said check valve, and sleeve valve means slideable with respect to said barrel to close said hole during lowering of said barrel in the well bore and to open said hole during elevation of said barrel in the well bore, said sleeve valve means including well bore wall engaging means for frictionally engaging the wall of the well bore to cause upward movement of the sleeve valve means to close the drain hole when the barrel is being lowered into a well and downward movement of the sleeve valve means relative to the barrel to open the drain hole when the barrel is being pulled out of the well bore.

2. A bailed adapted to be lowered in a well bore, including a barrel, a check valve at the lower end of said barrel capable of allowing upward passage of substances through said valve and into said barrel, an upper member telescopically arranged with respect to said barrel, said barrel having a bleeder passage therein, means on said upper member for closing said passage when said

member occupies an upper position with respect to said barrel, said barrel having a drain hole in its lower portion above said check valve, and a shoe slideable on said barrel to close said hole during lowering of said barrel in the well bore and to open said hole during elevation of said barrel in the well bore, said shoe having well bore engaging means for frictionally engaging the wall of the well bore to cause upward movement of the shoe to close the drain hole when the barrel is being lowered into the well bore and downward movement of the shoe relative to the barrel to open the drain hole when the barrel is being pulled out of the well bore.

3. A bailed adapted to be lowered in a well bore, including a barrel, a check valve at the lower end of said barrel capable of allowing upward passage of substances through said valve and into said barrel, said barrel having a drain hole in its lower portion above said check valve, and sleeve valve means slideable with respect to said barrel to close said hole during lowering of said barrel in the well bore and to open said hole during elevation of said barrel in the well bore, said sleeve valve means including well bore wall engaging means for frictionally engaging the wall of the well bore to cause upward movement of the sleeve valve means to close the drain hole when the barrel is being lowered into a well and downward movement of the sleeve valve means relative to the barrel to open the drain hole when the barrel is being pulled out of the well bore.

4. A bailed adapted to be lowered in a well bore, including a barrel, a check valve at the lower end of said barrel capable of allowing upward passage of substances through said valve and into said barrel, said barrel having a drain hole in its lower portion above said check valve, and a shoe slideable on said barrel to close said hole during lowering of said barrel in the well bore and to open said hole during elevation of said barrel in the well bore, said shoe having well bore engaging means for frictionally engaging the wall of the well bore to cause upward movement of the shoe to close the drain hole when the barrel is being lowered into the well bore and downward movement of the shoe relative to the barrel to open the drain hole when the barrel is being pulled out of the well bore.
